Patented May 1, 1917.

3 SHEETS—SHEET 3.

UNITED STATES PATENT OFFICE.

CHARLES L. RAYFIELD, OF CHICAGO, ILLINOIS.

CARBURETER.

1,224,203.

Specification of Letters Patent.

Patented May 1, 1917.

Application filed August 23, 1912. Serial No. 716,616.

To all whom it may concern:

Be it known that I, CHARLES L. RAYFIELD, a citizen of the United States, and a resident of the city of Chicago, in the county of Cook and State of Illinois, have invented certain new and useful Improvements in Carbureters; and I do hereby declare that the following is a full, clear, and exact description of the same, reference being had 5 to the accompanying drawings, and to the numbers of reference marked thereon, which form a part of this specification.

This invention relates to improvements in carbureters for internal combustion engines, 15 and has for its object, first, a preliminary supply of a rich mixture for the engine in starting, and thereafter with the opening of the throttle to vary the mixture as required to suit the load and speed commensurate 20 with the throttle opening.

It is an object of the invention to afford a construction wherein the air supply to the mixture under all running conditions, is controlled by the degree of throttle opening, 25 thus insuring perfect combustion and highest efficiency under all operating conditions.

It is an object of the invention to afford a construction whereby a given carbureter may be adjusted to supply the fuel requirements of any combustion engine, and in 30 which the adjustments having once been effected, remain constant under all conditions of load service.

It is also an object of the invention to afford a carbureter capable of ready and accurate adjustment by one not previously trained or skilled, and in which reliability and perfect fuel control is assured.

It is also an object of the invention to afford a construction whereby the throttle may be turned from high to low, or to any adjustment instantly, the engine responding perfectly for the adjustment and without back firing or missing.

It is an object of the invention also to afford an improved construction for more thoroughly mixing the charge, and in which vibration or fluttering of the controlling valve or valves because of the draft of the 50 motor thereon, or because of inequalities in the road, are absolutely precluded.

It is finally an object of the invention to afford a carbureter of the utmost simplicity, durability and efficiency, and adapted for 55 use under any and all conditions of service.

The invention (in a preferred form) is

illustrated in the drawings, and hereinafter more fully described.

In the drawings:

Figure 1 is a side elevation of a carbureter embodying my invention.

Fig. 2 is a top plan view thereof.

Fig. 3 is a section on line 3—3 of Fig. 2.

Fig. 4 is a section on line 4—4 of Fig. 3.

Fig. 5 is an enlarged fragmentary end elevation.

Fig. 6 is an enlarged, fragmentary detail, in which the by-pass of the fuel supply to a point beyond the throttle valve, is effected through the stem of the needle valve.

Fig. 7 is an enlarged section on line 7—7 of Fig. 4.

Fig. 8 is a section on line 8—8 of Fig. 4.

As shown in the drawings:

A casing of suitable metal or other material, is constructed to afford the float feed chamber A, and mixing chamber B, with related connections, and with the needle valve arranged intermediate said chambers. Said float feed chamber and mixing chamber may be constructed integrally, as shown, if preferred, said float feed chamber being cylindric in form, and provided axially at its bottom with an apertured internally threaded boss 1, in which is threaded 80 a plug 2, provided with a threaded aperture therein, in which may be engaged a pet cock to permit draining the float feed chamber should it be desired.

Said float feed chamber extends forwardly at its bottom and is provided in its bottom with an internally threaded boss 3, in which is threaded a plug 4, having a restricted aperture therethrough, which affords an upwardly facing valve seat, as 90 shown in Fig. 3, and threaded into the lower end of said plug is a union nut 5, whereby the gasoline (or other hydro-carbon supply pipe) is connected in the carbureter. Said forward extension of the float feed chamber 100 is provided near the middle of the height of said float feed chamber with a horizontal top wall 6, in which is threaded a nozzle 7, which opens upwardly therethrough in a restricted passage, and into which extends the needle 8, of the needle valve to regulate and control said passage, said needle, as shown, being integrally connected with a cylindric stem 9, slidably engaged in the 105 wall of the carbureter in axial alinement with said nozzle 7.

A needle valve is also provided to con-

trol the inlet of hydro-carbon fuel to the float feed chamber, and for this purpose the needle point 10, fits into the restricted aperture in the plug 4, before described, and is integrally connected with a sleeve 11, which extends upwardly and loosely receives the lower end of the nozzle 7, therein, as shown in Fig. 3. As shown, a double yoked lever 12, is pivotally supported upon a lug 13, secured in any suitable manner in the bottom of the float feed chamber between the needle valve and axis of said chamber, and, as shown, at one of its yoked ends engages around the sleeve 11, of the inlet needle valve engaged beneath a downwardly faced shoulder thereon, and at its other end receives the stem 14, of the float 15, in said float feed chamber therein, a ball 16, on said stem, bearing upon the top of said yoke, as shown in Fig. 3, and affording a ball and socket joint thereon, and said float, as shown, being adjustably supported on the stem 14, by means of a clamping collar 17, secured on said float and through which said stem extends, so that with the rising of the float above normal, the inlet needle valve seats and closes by gravity. With the descent of the float in the float feed chamber due to depletion of the gasoline supply therein, the needle valve 10, is raised, permitting inflow of the hydro-carbon fuel, thus maintaining a constant level in the float feed chamber.

An air inlet passage 18, is provided, opening into the mixing chamber at the bottom thereof, and integral with the bottom of said mixing chamber, and extending axially upward thereinto is a sleeve 19. Below the floor or bottom 20, of the mixing chamber is a dash pot chamber, the walls 21, of which are integral with the bottom of the mixing chamber, and are internally threaded and closed at their lower edge with a screw plug 22, threaded thereinto and properly gasketed. As shown, a passage 23, opens from the float feed chamber into the dash pot chamber, and fitting loosely in said chamber is a piston 24, provided with a stem 25, which extends upwardly through the sleeve 19, and above the same, and secured on which at its upper end is a double puppet valve 26 and 27, which is integrally connected by a stem 28, bored to receive the sleeve 19, axially and loosely thereinto, said bore being of a length to permit said valves to fully seat or close.

The lower of said puppet valves 26, seats in, and closes an aperture in a substantially horizontal floor 29, above and parallel with the floor or bottom 20, before described, and the stem 28 thereof extends upwardly therefrom and from a point below the puppet valve 27, flares outwardly to near the periphery of the puppet valve 27, affording

a concave under wall thereof to spread and deflect the upwardly flowing mixture peripherally around the same. Said upper puppet valve seats to close the mixing chamber at substantially the level of the top of the float feed chamber, as shown in Fig. 3, and is secured on the upper end of the stem 25, by means of a pin 30, extending therethrough.

As shown, the top of the carbureter, including the top 31, for the mixing chamber, and the cover 32, for the float feed chamber, integrally connected and carrying therein the various regulating mechanisms for adjusting and controlling the carbureter, is rigidly secured in place by means of cap screws 33, and screws 34, or in any other suitable manner. As shown, the walls affording the upper portion of the mixing chamber first diverge outwardly from the top of the puppet valve 27, thence converge inwardly to the top thereof, and are integrally connected with the apertured flange 35, whereby the carbureter may be attached to the manifold of the engine, and journaled through the top 31 on a shaft 36, is the butterfly throttle valve 37, adapted to wholly close the mixing chamber from the manifold. As shown, a throttle lever 38, is secured on the outer end of the shaft 36, for said throttle valve to permit the same to be actuated. Any suitable means, as, for instance, the stop 39, integral with 38, and set screw 40, at one side said throttle lever, may be provided to limit the throw thereof in one direction to full opening, while any suitable stop 41, also integral with lever 38, serves to limit the adjustment thereof to the other or fully closed position, as shown in Figs. 1 and 2, said stops contacting the integral lug 35^a, on the flange 35 when in the aforesaid positions.

Means are provided for accurately adjusting the needle valve to suit the requirements of low speed. For this purpose the stem 9, of the needle valve, which extends upwardly into a suitable seat 42, therefor in the upper or cover portion of the carbureter, is provided with a spring 43, which acts to hold said needle valve normally downward to closed position. Extending through the housing 44, integral with said cover, and above said needle valve, is a shaft 45, on which is secured an arm 46, which extends into a V-shaped slot in the stem 9, of the needle valve, as shown in Fig. 3, so that rotation of said shaft in one direction acts to elevate the stem of the needle valve to open the needle valve, and in the opposite direction acts to close said valve.

Rigidly secured on the outer end of said shaft 45, is an upwardly extending arm 47, having a threaded bore at the top thereof directed at a right angle with the shaft 45, and having threaded therein a set screw 48,

provided on its outer end with a milled head 49, adapted to be held in adjustment by means of a detent 50, set in an arm 51, integral with said arm 47.

- 5 Secured on the shaft 45, and extending through the removable side wall 52, for said housing, is a sleeve 53, as shown in Fig. 4, having a rocker arm 54, rigidly secured at the inner end thereof and slotted or yoked 10 on its under side at its extremity, and provided with a bearing pin 54^a at the throat of said yoke. Rigidly secured on said sleeve at its outer end and at the inner side of the arm 47, before described, and offset therefrom, is an upwardly extending sleeve 55, in which is journaled a shaft 56, having an eccentric 57, rigidly secured thereon in position to bear against the inner end of the set screw 48.
- 20 Rigidly secured at the upper end of said shaft 56, is a lever 58, which is directed transversely of the carburetor as shown in Fig. 2, and to the extremity of which is connected a wire or cable 59, which leads to a 25 suitable bracket 60, secured on the top of the carburetor, and through a pipe 61, and to a suitable button or pull positioned conveniently to the operator.

As shown in Fig. 3, an unobstructed air 30 inlet passage 62, is provided adjacent to, and slightly above the nozzle 7, of the needle valve to supply air at all times directly across the nozzle. As shown, a slightly raised lip or dam 64, is provided at the inner 35 edge of the floor or horizontal wall through which said nozzle opens to retain a small amount of the hydro-carbon exposed thereon for vaporization. A by-pass pipe 65, extends from near the surface of the hydro-car- 40 bon on said floor upwardly through the top wall of the carburetor, and opens by means of a passage 67, above the throttle valve into the manifold pipes, or, if preferred, the stem 9, of the needle valve may be bored to af- 45 ford a passage 66, therethrough, continuing in a passage 67^a, in the top of the carburetor, and opening above the throttle valve as before described.

An integral hub or collar 68, is provided 50 on the upper face of the puppet valve 27, through which the pin 30, (whereby the puppet valve is secured on the stem) extends. Said hub is extended laterally and is provided with an upwardly opening slot 55 thereto, as shown in Fig. 4, and slidably supported therein is a lever 69, which extends alongside the stem 9, of the needle valve, and at its extremity is pivotally en- 60 gaged by means of a pin 70, upon a rod 71, which is threaded at its other extremity and has threaded engagement in an internally threaded sleeve 72, rotatably seated in a horizontal bore provided in the top of the cover for the float feed chamber. Said 65 sleeve is provided at its outer end with a

milled head 73, which engages in a notch or recess in the upper edge of the bracket 74, secured on the side of the float feed chamber integrally, if preferred, and in which is a spring pressed detent 75, shown in dotted lines in Figs. 1 and 5, and which engages the milled periphery of said head and normally holds the same from rotation. The rocker arm 54, at its yoked end fits over said lever 59, as shown in Figs. 4 and 8. Consequently, adjustment of the lever 69, longitudinally by means of rotation of said sleeve 72, varies the distance of the bearing of said rocker arm on said lever from the fulcrum for the lever just above the pin 70.

As shown, a butterfly valve 76, is secured upon the shaft 77, to control the main air supply passage, and a lever 78, is secured on the outer end of said shaft 77, and is provided with notches 79, at ninety degrees apart, adapted to be engaged by a spring pressed detent 80, as shown in Figs. 1, 2 and 4, said detent acting to hold said valve either at fully open position or fully closed position, dependent upon which of said notches is engaged by said detent. This air inlet valve may be operated independently from the dash, if desired, and ordinarily is left fully open. It may, of course, be controlled by mechanical connection between the same and the throttle lever 38, if desired. If unconnected therewith, however, it serves a valuable purpose in protecting the device from unauthorized interference, or theft, inasmuch as when said valve is fully closed, as shown in Fig. 3, the engine can only be operated at the slowest rate.

The operation is as follows:

In setting the carburetor, the set screw 48, is adjusted against the sleeve 57, to afford a sufficient elevation of the needle valve closure to supply a very limited flow of the hydro-carbon, but sufficient to operate the engine at lowest speed, the air to supply the very rich mixture being admitted through the constantly open air port 62, adjacent the needle valve, and the rich mixture afforded thereby passing up through the pipe and passage 65, to a point above the throttle valve, which remains practically closed, and, of course, shutting off nearly all supply of mixture or air through the puppet valves and butterfly valves hereinbefore described. The pressure of the set screw 48, against the cam 55, and the tension exerted by the spring 43, to hold the needle valve closed, is opposed by the pressure of the rocker arm 54, on the lever 69. In consequence, the low speed adjustment effected by the set screw 48, remains as a constant adjustment for low speeds and insures the same degree of opening for said needle valve at all times when the throttle is closed.

When it is desired to increase the flow of hydro-carbon through the needle valve, in

starting and particularly in cold weather, the shaft 56, is rotated by a pull on the cable 59, bringing the cam 57, into engagement with the set screw 48, and further elevating 5 the needle valve against the tension of its spring. Immediately upon release, however, of the cable or wire 59, the spring 43, acts to return the needle valve to its adjusted position and all parts to normal.

10 The opening of the throttle valve 37, and air inlet valve 76, brings the puppet valve into action. The air supply through the constantly open port 62, brings an exceedingly rich mixture into the space between 15 the puppet valves. Additional air is admitted past the valve 76, from the valve 26, and after mixing with the air and fuel already admitted as mentioned, is delivered peripherally around the puppet valve 27, and 20 thence into the manifold past the throttle valve. The dash pot afforded by the gasoline chamber below the mixing chamber in which the piston 24, secured on the stem 25, is placed, insures the uniform operation 25 of the puppet valves under all conditions. Said dash pot holds said valves from fluttering due to the possible unequal action of the cylinders or due to vibrations occasioned through the operation of the vehicle, or 30 other device, and limits the movement of said valves to the proper requirements of the engine.

The adjustment of the hydro-carbon supply for high speed is effected through the 35 medium of the lever 69. This is adjusted longitudinally by means of rotation of the milled head 73, which threads the shaft 71, into or out of the sleeve 72, thereby varying the distance of the fulcrum pin 70, from 40 the bearing pin 55, in the end of the yoke, and with a given elevation of the free end of said lever 59, the greater the distance between said fulcrum pin 70, and bearing pin 55, the greater the opening of the needle 45 valve through the medium of the shaft 45, and arm 46. Consequently, a very accurate adjustment may be thereby effected to adapt the supply of the hydro-carbon to the requisite air supply to afford perfect combustion 50 at the highest attainable speed. Any intermediate throttle adjustment lifting the puppet valves to proportionately a less height, affords decreased flow of hydro-carbon and consequently the supply is at all times exactly adjusted to the requirements of the engine.

It is, of course, to be understood that I have shown but a preferred form of my invention, and I am aware that details of the 60 construction and operation may be varied through a wide range. I therefore do not purpose limiting the patent granted on this application otherwise than necessitated by the prior art.

I claim as my invention:

1. A carburetor embracing a source of hydro-carbon supply, a valve controlling the same, a mixing chamber in open communication with the hydro-carbon from said valve, connected valves affording the top and bottom of said chamber, a throttle valve above the same, an air inlet passage below the same, a normally open air port adjacent the needle valve, a passage leading from near the needle valve into the manifold beyond the throttle valve, and adjustable means affording an initial opening of the needle valve independently of the opening of the throttle.

2. In a carburetor of the class described, 80 a source of hydro-carbon supply, a needle valve controlling the same, a mixing chamber to receive the supply from the needle valve, a normally open air inlet adjacent the needle valve, a throttle valve controlling the flow of mixture from the carburetor, a by-pass passage leading from near the needle fuel valve into the outlet from the carburetor beyond said throttle valve, a gravity acting valve to control the flow 90 from the mixing chamber toward said throttle valve, operative connections between the same and said needle valve, and regulable means affording a constant opening of said needle valve for operation of the engine at 95 low speed independently of said second mentioned outlet valve.

3. In a carburetor a source of hydro-carbon supply, a needle valve controlling the same, an air port adjacent the needle valve, 100 a mixing chamber, throttle and controlling outlet valves therefor, a dash pot controlling one of said valves, and a passage leading from near the needle valve to the manifold and adapted to deliver a rich mixture 105 into the manifold prior to the opening of said valves.

4. A carburetor embracing a source of hydro-carbon supply, a needle valve controlling the same, a mixing chamber, a throttle outlet valve, a controlling outlet valve therein operable independent of the throttle valve, a lever connected with said controlling valve and acting to control the opening of the needle valve, and a passage 110 leading from the needle valve around said controlling valve to deliver a rich mixture 115 into the manifold when said valve is closed.

5. In a device of the class described a mixing chamber comprising the side walls and upper and lower automatic puppet valves affording the top and bottom respectively of said chamber, a dash pot, a piston therein, a stem secured to said piston and connected with said valves, a needle valve controlling the supply to the mixing chamber, and operative connections between the needle valve and one of said valves to regu-

- late the opening of the needle valve in proportion to the opening of said valves.
6. In a carbureter a source of hydro-carbon supply, a needle valve, a mixing chamber to receive the supply from the needle valve, a constantly open air inlet port to said mixing chamber, a throttle valve, a passage leading from the mixing chamber into the manifold to supply a rich mixture thereto when the throttle is closed, a control valve normally closing the outlet from the mixing chamber and operated automatically, a lever operated by said valve and operatively connected with the needle valve to open said needle valve proportionately with the lift of said valve, and means adjusting said lever to vary the lift of the needle valve.
7. In a device of the class described an automatically acting puppet valve controlling the discharge of mixture to the manifold when the throttle valve is open, a lever adjustably connected therewith and operatively connected with the supply valve for the hydro-carbon, and acting to adjust the opening of said valve to correspond with the degree of opening of said puppet valve, and means adjusting said lever to vary the opening of the supply valve with a given lift of said puppet valve.
8. In a device of the class described a source of hydro-carbon supply, a needle valve controlling the same, embracing a nozzle and a reciprocable stem, a spring tending to hold said stem normally in closing position, a bell crank lever engaged to lift the stem, a set screw mounted in said bell crank adapted to lift the stem of the needle valve against the tension of its spring, and an automatically actuated lever acting on said bell crank to vary the lift of the needle valve with the rate of mixture consumption, and connected inlet and outlet valves adapted to actuate said lever.
9. In a device of the class described means affording a rich mixture for preliminarily starting the engine, and including mechanism affording a regulable opening for the fuel supply valve, a constantly open air inlet port thereto and a by-pass passage through which the rich mixture is delivered past the throttle valve, automatically acting valves operating when the throttle valve is open to supply a mixture to the engine, and a lever operated by one of said valves and acting to vary the opening of the supply valve to the rate of mixture consumption.
10. In a carbureter of the class described, a source of hydro-carbon supply, a valve controlling the discharge therefrom, a mixing chamber to receive said supply disposed so as to be normally in open communication with the flow from said needle valve, an automatically operating valve affording one wall of said mixing chamber, a dash pot in communication with the hydro-carbon supply to control the operation of said automatic valve, an air inlet valve for the carbureter positively operated by said automatically acting valve and also controlling the inlet of air to said automatically operating valve, and a lever operated by said automatically acting valve to vary the degree of opening of the hydro-carbon supply valve.
11. In a carbureter of the class described, a mixing chamber, connected automatically acting valves controlling the inlet and outlet thereof, an inlet hydro-carbon valve in open communication with said mixing chamber in the space between said inlet and outlet valves, means retarding the movement of said inlet and outlet valves, and operative connections between said inlet and outlet valves and said needle valves.
12. In a device of the class described a mixing chamber, a needle fuel valve therein, an air port adjacent thereto, connected valves affording an inlet and outlet to said mixing chamber, a dash pot connected with said valves and with the source of fuel for said needle valve, and a throttle valve disposed to control the flow of mixture beyond the outlet valve of said mixing chamber.
13. In a device of the class described a needle valve, a mixing chamber, an air inlet valve therein, a mixture outlet valve adapted to be operated by the suction of the cylinders of an engine, and a throttle valve disposed beyond said mixture outlet valve to govern the suction on said valves on the opening thereof, and means connecting said mixture outlet valve with said air inlet valve to proportionately open the latter with movement of said outlet valve.
14. In a device of the class described a mixing chamber, connected valves affording inlet and outlet therein, a fuel valve connected therewith and operable thereby, an air port adjacent said valve and acting to maintain said mixing chamber at atmospheric pressure, and a throttle valve connected beyond said mixing chamber outlet valve to govern the opening of the latter by controlling the differences of pressure thereon.
15. In a device of the class described a mixing chamber, an automatic outlet valve therein, an inlet air valve operated by said outlet valve, and means connected with said outlet valve to open the fuel valve with a corresponding movement of said mixing chamber outlet valve, said fuel valve disposed in open communication with the space between said outlet and inlet valves.
16. In a device of the class described a throttle valve, an air inlet valve, connected inlet and outlet mixing chamber valves dis-

- posed between said throttle valve and said inlet air valve, a fuel valve, and adjustable means connected between the same and said inlet and outlet valves to insure proportionate opening of each.
17. A carbureter comprising a mixing chamber, a manually operatable inlet valve therefor, a manually operatable throttle outlet valve therefor, automatic inlet and outlet valves disposed between said manually operated valves, a fuel valve and means connected with said fuel valve and said automatic valve to insure proportionate opening of each.
18. In a device of the class described a mixing chamber, manually operatable valves controlling the inlet and outlet therefrom, automatically operated inlet and outlet valves in said mixing chamber disposed intermediate said manually operatable valves, a fuel valve connected to open with a corresponding movement of said automatic valves, and means to prevent fluttering thereof.
19. In a device of the class described a mixing chamber, manually operatable inlet and outlet valves therefor, automatic valves interposed therebetween, a fuel valve connected with said automatic valves to insure proportionate opening of each, an auxiliary fuel passage affording a flow of fuel mixture when all of said valves except the fuel valve are closed, and means connecting said fuel valves and said automatic valves.
20. In a carbureter, the combination with a casing having an air intake and a float chamber, of automatically-controlled connected mixture outlet and air intake valves, a lever adapted to be actuated by said valves, a fuel valve, and a second independently fulcrumed lever engaging the fuel valve and adapted to be actuated by the first said lever.
21. In a carbureter, the combination with a casing having an air intake and a float chamber, of an automatically-controlled air intake valve, a mixture outlet valve connected thereto for movement therewith, a fuel valve, a lever adapted to be actuated by said connected valves and bodily adjustable to vary the distance between its fulcrum and the point of engagement with the air valve, and an independently fulcrumed lever connected with the fuel valve and adapted to be actuated by the first said lever.
22. In a carbureter, the combination with a casing having an air intake and a fuel inlet, of an automatically-controlled air intake valve, a mixture outlet valve connected thereto, a fuel valve, two levers, one adapted to be actuated by said connected valves to rock the other and the latter engaging the fuel valve, and means for varying the relation between said levers, for the purpose described.
23. In a carbureter, the combination with a casing having an air intake and a fuel inlet, of connected automatically-controlled intake and outlet valves, a fuel valve, two independently fulcrumed levers, one engaging at its free end with the fuel valve and the other adapted to be actuated by the automatically-controlled valves, and an adjustable connection between said levers.
24. In a carbureter, the combination with a casing having an air intake and outlet and a fuel inlet, of automatically-controlled intake and outlet valves, a fuel valve, two independently fulcrumed levers, one engaging at its free end with the fuel valve and the other adapted to be actuated by the automatically-controlled valves, a connection between said levers, and means for bodily shifting one of said levers to vary its effective length.
25. In a carbureter, the combination with a casing having an air intake and a float chamber, of automatically-controlled intake and outlet valves, a lever adapted to be actuated by said valves, a fuel valve, and a second lever engaging the fuel valve and extending substantially parallel to and adapted to be actuated by the first said lever.
26. In a carbureter, the combination with a casing having an air intake and a fuel inlet, of automatically-controlled connected valves, a fuel valve, two levers, one adapted to be actuated by said connected valves to rock the other and the latter engaging the fuel valve, and means for shifting one of said levers bodily to vary the relative movements of the valves.
27. In a carbureter of the class described, a mixing chamber, an air inlet to said mixing chamber, a mixture outlet from said mixing chamber, suction controlled valves in said air inlet and said mixture outlet connected so that each opens and closes harmoniously with and relative to the other, a fuel inlet discharging into said mixing chamber between said air inlet and said mixture outlet, means operable by the movement of said valves for varying the discharge capacity of said fuel inlet correspondingly with the position of said valves.
28. In a carbureter of the class described, a mixing chamber, an air inlet to said mixing chamber, a mixture outlet from said mixing chamber, suction controlled valves in said air inlet and said mixture outlet connected so that each opens and closes harmoniously with and relative to the other, a carbureting chamber having air and fuel inlets, said chamber discharging into said mixing chamber between said air inlet and said mixture outlet valves, means operable by the movement of said valves for varying the discharge capacity of said fuel inlet.
29. In a carbureter of the class described, a mixing chamber, an air inlet to said mix-

ing chamber, a mixture outlet from said mixing chamber, suction controlled valves in said air inlet and said mixture outlet connected so that each opens and closes harmoniously with and relative to the other, a fuel inlet discharging into said mixing chamber between said air inlet and said mixture outlet and means opposing suction for returning said valves to their normal position, and means for retarding the movements of said valves.

30. In a carbureter of the class described, a mixing chamber, an air inlet to said mixing chamber, a mixture outlet from said mixing chamber, suction controlled valves in said air inlet and said mixture outlet, a

fuel inlet discharging into said mixing chamber between said valves, a needle valve in said fuel inlet, means controlled by the movements of said valves for varying the discharge capacity of such fuel inlet corresponding with the position of said valves, and means for altering and adjusting the ratio of movement between said air and mixture valves and said needle valve.

In testimony whereof I have hereunto subscribed my name in the presence of two subscribing witnesses.

CHARLES L. RAYFIELD.
